his Attorneys.

UNITED STATES PATENT OFFICE.

ALFRED HJELM, OF WESTBY, MONTANA, ASSIGNOR TO LOCK POCKET GARMENT COMPANY, OF MINNEAPOLIS, MINNESOTA, A CORPORATION.

DUPLEX POCKET.

1,355,044.

Specification of Letters Patent.

Patented Oct. 5, 1920.

Application filed February 10, 1919. Serial No. 276,142.

To all whom it may concern:

Be it known that I, ALFRED HJELM, a citizen of the United States, resident of Westby, county of Sheridan, State of Montana, have invented certain new and useful Improvements in Duplex Pockets, of which the following is a specification.

The object of my invention is to provide a means for closing the mouth of a pocket which will be simple and inexpensive and easily applied to the pocket and will dispense with all spring plates or other metallic parts frequently used in pockets of this kind.

15 A further object is to provide a pocket adapted for garments generally and particularly applicable to the bib or apron portion of overalls.

Other objects of the invention will appear 20 from the following detailed description.

The invention consists generally in various constructions and combinations, all as hereinafter described and particularly pointed out in the claims.

25 In the accompanying drawings forming part of this specification,

Figure 1 is a front view of a pocket embodying my invention,

Fig. 2 is a vertical sectional view of the 30 same,

Fig. 3 is a view showing the arrangement of the flaps in the pocket,

Fig. 4 is a sectional view showing the pocket inverted,

35 Fig. 5 is a sectional view, showing the pocket opened for the reception of articles to be placed therein.

In the drawing, 2 represents the wall of the garment on which the pocket is to be 40 mounted. 3 is the front wall of the pocket, stitched at the bottom 4 and at the sides 5 to the wall of the garment 2, an opening 6 being left at the top to form the mouth of the pocket. 7 is a flap, preferably folded to

45 form a double thickness to obtain the desired degree of stiffness, stitched at 8 to the inner face of the pocket 3 and extending across the pocket below the mouth thereof. The upper edge of this flap is free and may

50 swing back and forth on the stitched portion 8. 9 is a flap, secured to the garment wall 2 at 10 and depending within the open mouth

of the pocket and having its lower edge lapping by the upper edge of the flap 7 and for the purpose of holding these edges in their 55 proper lapping position I prefer to stitch the lower edge of the flap 9, as indicated at 11, to the ends of the flap 7 so that when these flaps are separated the lower edge of the flap 9 will always have a tendency to slip 60 in between the pocket 3 and the upper edge of the flap 7. When an article is to be inserted in the pocket, the flap 9 is lifted to allow the insertion of the article between the flaps and between the flap 7 and the wall 65 2 into pocket 12 beneath.

In Fig. 2 I have indicated coins 13 in the bottom of this pocket. Now, assuming that the parts are in the position shown in Fig. 2, if the apron or bib of the overall be 70 dropped down so that when the pocket is inverted, as indicated in Fig. 4, the coins, watch, knife or other article which may be in the bottom of the pocket will immediately drop by gravity and the mouth of the pocket, 75 being closed by the lapping flaps 7 and 9, the articles will drop into the secondary or auxiliary pocket 14 provided between the flap 9 and the garment wall 2 and will thereby be prevented from dropping out of the 80 pocket and being lost. As soon as the pocket has been returned to its proper position, the articles contained in the auxiliary pocket 14 will drop back by gravity into the main pocket 12 where they can be easily 85 reached by inserting the hand between the flaps 7 and 9. With this arrangement of the flaps I dispense entirely with all spring plates or any metallic parts which add to the expense of manufacture of the pocket 90 without in any way limiting the scope of the field in which the pocket may be used.

I claim as my invention:

1. The combination, with a garment wall, of a pocket wall secured thereto and having 95 an opening forming the mouth of the pocket, flexible flaps attached respectively to the pocket wall and the garment in said mouth and having lapping edges and means securing said lapping edges together only at the 100 opposite sides of the pocket to hold the free central portion of the garment flap in its working position between the pocket wall and the pocket flap.

2. The combination, with a garment wall, of a pocket wall secured thereto and having an opening forming the mouth of the pocket, flexible flaps mounted respectively on the 5 garment wall and the pocket wall and having their meeting edges within the pocket lapping by one another and the edge of one

flap being stitched at its ends to the other flap at points intermediate to the longitudinal edges thereof, for the purpose specified. 10

In witness whereof, I have hereunto set my hand this 3d day of February 1919.

ALFRED HJELM.
